CLAIM

The ornamental design for a dispenser for deodorant or other topical product, substantially as shown.

DESCRIPTION

FIG. 1 is a perspective view of a dispenser for deodorant or other topical product showing my new design;
FIG. 2 is a front elevational view thereof, with the axial member vertically disposed;
FIG. 3 is a rear elevational view;
FIG. 4 is a top plan view;
FIG. 5 is a bottom plan view; and
FIG. 6 is a side elevational view, the other side being identical to the view shown.

FIG. 1

FIG. 2

FIG. 3

FIG. 4

FIG. 6

FIG. 5
